UNITED STATES PATENT OFFICE

119,331

DESIGN FOR A SAW SETTING BLOCK

Fredrick W. Wilson, Port Orchard, Wash.

Application July 10, 1939, Serial No. 85,943

Term of patent 14 years

To all whom it may concern:

Be it known that I, Fredrick W. Wilson, a citizen of the United States, residing at Port Orchard, in the county of Kitsap and State of Washington, have invented a new, original, and ornamental Design for a Saw Setting Block, of which the following is a specification, reference being had to the accompanying drawing, forming part thereof.

Figure 1 is a side elevational view of a saw setting block showing my new design.

Figure 2 is an end elevational view thereof looking from left to right in Figure 1.

Figure 3 is a top plan view of Figure 1.

The essential features of my design reside in the substantially rectangular body member in combination with the outwardly and upwardly extending handle of the specific configuration shown.

I claim:

The ornamental design for a saw setting block, as shown and described.

F. W. WILSON.
